(57) **CLAIM**

The ornamental design for a plumbing fitting, as shown and described.

DESCRIPTION

FIG. 1 is a bottom perspective view of a plumbing fitting showing our new design;

FIG. 2 is a bottom plan view thereof;

FIG. 3 is a side sectional view taken along line 3-3 of FIG. 2;

FIG. 4 is a rear looking sectional view taken along line 4-4 of FIG. 2;

FIG. 5 is a front looking sectional view taken along line 5-5 of FIG. 2;

FIG. 6 is a bottom perspective view of a plumbing fitting showing another embodiment of our new design;

FIG. 7 is a bottom plan view thereof;

FIG. 8 is a side sectional view taken along line 8-8 of FIG. 7;

FIG. 9 is a rear looking sectional view taken along line 9-9 of FIG. 7; and,

FIG. 10 is a front looking sectional view taken along line

10-10 of FIG. 7.

The broken lines depict portions of the article that form no part of the claimed design.

The nature of this product is a plumbing fitting, such as a

spout, or portion thereof, for a sensor activated faucet.
